APPARATUS FOR EFFECTING OPERATION
OF PRESSURE OPERATED MECHANISMSJames K. Douglas, Shorewood, Wis., assignor to
The Oilgear Company, Milwaukee, Wis., a cor-
poration of Wisconsin

Application April 8, 1949, Serial No. 86,276

5 Claims. (Cl. 60—52)

1

This invention relates primarily to apparatus for exercising the recoil mechanisms of artillery but the invention is not limited to such use.

An ordinary type of recoil mechanism for a gun includes a recoil cylinder and a recuperator cylinder, both of which are arranged parallel to the gun barrel and are fastened thereto, a floating piston which is fitted in the recuperator cylinder and a recoil piston which is fitted in the recoil cylinder and is fixed to a piston rod which extends through the front end of the cylinder, that is, the end of the cylinder toward the muzzle of the gun. The outer end of the piston rod is fastened to the cradle which supports the gun. The recoil cylinder and the portion of the recuperator cylinder in front of the floating piston are filled with oil and are connected to each other by a suitable passage. The recuperator cylinder at the rear of the floating piston is filled with a compressed gas, such as nitrogen, which urges the floating piston forward and thereby maintains the oil under pressure.

When the gun recoils due to being fired, the two cylinders move with it and the recoil piston, being stationary, forces oil out of the recoil cylinder into the recuperator cylinder and the oil forces the floating cylinder rearward against the gas which cushions and checks the recoil and then causes the floating piston to move forward and force oil out of the recuperator cylinder and into the recoil cylinder to thereby return the gun to firing position.

The relative movements of the pistons and cylinders keeps the surfaces of the pistons lubricated when the gun is in service but during time of peace a great many guns are placed in storage and, if they were allowed to remain entirely inactive, the lubricating film between the pistons and the walls of the cylinders would disappear and the pistons would stick to the walls of the cylinders, thereby seriously damaging the recoil mechanisms.

In order to avoid such damage, the recoil mechanisms of guns in storage are "exercised," that is, relative movement between each piston and its cylinder is effected to thereby re-establish a lubricating film between each piston and the wall of its cylinder, only a short relative movement being necessary to re-establish the film. Some completely assembled guns are placed in storage and other guns are partially disassembled before being placed in storage so that it sometimes is desirable to exercise a recoil mechanism as a unit and at other times to exercise the parts individually.

2

The type of "exerciser" currently used includes a reversible pump, a "cylinder line" for conveying oil from the pump to one end of one of the cylinders of the recoil mechanism or to the adjacent ends of both of the cylinders to effect movement of one or both of the two pistons, a hydraulic jack for moving the recoil piston in the opposite direction, a "jack line" for conveying oil from the pump to the jack, a meter for measuring the amount of oil delivered to or discharged from a cylinder to thereby indicate the distance through which a piston is moved, and valves and other controls including a plurality of push button switches by means of which operation of the exerciser is controlled.

The prior exerciser would exercise recoil mechanisms as explained above but it had certain objectionable features and extreme care was necessary when using it. For example, if the operator should first close the switch which causes oil to be pumped to the recuperator cylinder to move the floating cylinder rearward and thereby further compress the gas in the cylinder and then he should inadvertently close the switch which causes the exerciser to operate automatically, the gas pressure would force oil out of the cylinder and through the meter at such a high velocity that the meter would be driven so fast and the drop in pressure across the meter would be so great that the meter would be ruined or seriously damaged.

The present invention has as an object to improve the prior exerciser.

Another object is to prevent the meter of an exerciser from being operated at such high speed that it might be damaged.

Other objects and advantages will appear from the following description of the exerciser shown schematically in the accompanying drawing in which the views are as follows:

Fig. 1 is a diagram of the hydraulic circuit of an exerciser in which the invention is embodied, the exerciser being shown connected to the recoil mechanism of a particular type of gun.

Figs. 2 and 3 are views showing two valves in positions different from those shown in Fig. 1.

The recoil mechanism of a gun and an exerciser are both complicated mechanisms but all parts not necessary to an understanding of the invention have been omitted from the drawing which is purely schematic.

The exerciser is adapted to exercise the recoil mechanisms of all types of guns and it has been shown connected to a recoil mechanism which includes a recuperator cylinder having a float-

ing piston 2 fitted therein, a recoil cylinder 3 having a recoil piston 4 fitted therein and a piston rod 5 which is fixed to piston 4 and extends through the end of cylinder 3 for connection to the front end of the cradle (not shown) of the gun. Floating piston 2 divides cylinder 1 into a gas chamber 6 and a liquid chamber 7 which is connected by a passage 8 to cylinder 3 adjacent the front end thereof which is the right end in respect to the drawing. Chamber 7 and cylinder 3 normally are filled with oil and chamber 6 is filled with a compressed gas, such as nitrogen, which maintains pressure upon the oil in cylinder 3 and chamber 7 when the recoil mechanism is in operation.

Movement of the floating and recoil pistons toward the left relatively to the cylinders is effected by pumping oil into the right ends of the cylinders. Movement of the recoil piston toward the right is effected by means of a hydraulic jack which includes a piston 9 fitted in a cylinder 10 and provided with a piston rod 11 and which is attached to the recoil cylinder after removal of the plug (not shown) which normally closes the left end of the recoil cylinder.

In order that the exerciser may be employed to exercise the recoil mechanisms of a large variety of guns, the hydraulic jack is attached to the recoil cylinder by means of an adapter one of which is provided for each kind and size of recoil mechanism. In some instances, an adapter is fitted over the end of a recoil cylinder and is fastened thereon by suitable clamping means and in other instances an adapter is threaded into the end of the recoil cylinder. As shown, an adapter 12 is threaded into the end of cylinder 3 and the jack 9-11 is inserted into adapter 12 and is fastened thereto by a bayonet joint 13.

Oil for operating jack 9-11 and for moving pistons 2 and 4 toward the left is supplied by a reversible variable delivery pump 17 which is supercharged by gear pump 18 and discharges oil into either a channel 19 or a channel 20. Gear pump 18 draws oil from a reservoir 21 and discharges it into a channel 22 which is connected through two check valves 23 and 24 to channels 19 and 20 respectively. The arrangement is such that gear pump 18 can deliver oil through one check valve 23 or 24 into the channel 19 or 20 which is connected to the intake of pump 17 and the other check valve 23 or 24 will prevent the oil discharged by pump 17 from entering channel 22.

Gear pump 18 has been shown separate from pump 17 and is being provided with a separate relief valve 25 through which oil pumped by gear pump 18 in excess of requirements is exhausted but in practice gear pump 18 and relief valve 25 are incorporated in pump 17 which also has incorporated therein suitable relief valves for limiting the pressure of the oil discharged into channels 19 and 20.

The oil delivered to and discharged from cylinder 3 and chamber 7 passes through a hydraulic motor 26 which drives an indicating and control mechanism 27 and which functions as a meter to measure the amount of oil passing therethrough to thereby cause the indicating mechanism to indicate the extent of movement of piston 2 and/or the extent of movement of piston 4.

Flow of oil to and from the cylinders and the jack is controlled in the first instance by a start and stop valve which includes a valve member 30 fitted in a valve body 31 having four annular

grooves or ports 32, 33, 34 and 35 formed therein. Port 32 has a branch of channel 19 connected thereto and port 33 is connected by a channel 36 to meter 26.

Port 34 has connected thereto a channel 37 which has a shut off valve 38 arranged therein and which is connected by a flexible channel or "jack line" 39 to jack cylinder 10. Port 35 communicates with a channel 40 which is connected through a shut off valve 41 to one end of a flexible channel or "cylinder line" 42 to the other end of which is adapted to be connected to cylinder 1. Jack line 37 and cylinder line 42 are connected, respectively, through two shut off or "bleeder valves" 43 and 44 to two channels 45 and 46 which in practice discharge into reservoir 21 but which have been shown as discharging into two auxiliary reservoirs 21^a and 21^b in order to avoid complicating the drawing.

The front end head of cylinder 1 has extending therethrough a passage 47 which contains a "filling valve" (not shown) and which is closed at its outer end by a plug (not shown) when the recoil mechanism is in operation. Cylinder line 42 may be connected to cylinder 1 by removing the plug from passage 47, screwing a "charging valve" 48 into the end of passage 47, connecting cylinder line 42 to valve 48 and then opening the "filling valve" by turning the knob 49 on valve 48 so that oil can flow through cylinder line 42 to and from chamber 7.

When the exerciser is in operation, oil discharged from the recoil mechanism through cylinder line 42 is directed either to reservoir 21^b or to the intake of pump 17 by a valve 55 which is fitted in the bore 56 of a valve body 57 to control communication between five annular grooves or ports 58, 59, 60, 61 and 62 formed in the wall of bore 56. Port 58 has channel 20 connected thereto. Port 59 is connected to meter 26 by a channel 63. Port 60 communicates with a channel 64 which discharges into reservoir 21. Port 61 has a branch of channel 19 connected thereto. Port 62 is connected to gear pump channel 22 by a channel 65 which also is connected to the end of bore 56.

Valve 55 is urged toward the right to the position shown in Fig. 1 by gear pump pressure and by a spring 66, and it is adapted to be shifted toward the left to the position shown in Fig. 2 by oil supplied to port 58 from pump 17 or by a servomotor comprising a piston 67 fitted in a cylinder 68 which is formed in or attached to valve body 57 and is connected by a channel 69 to channel 40.

The exerciser mechanism is carried by a two-wheeled trailer which may be moved close to the recoil mechanism to be exercised. In order to simplify the drawing, jack line 39 and cylinder line 42 have been shown as being relatively short but in practice they are long enough to reach from the trailer to opposite ends of the recoil mechanism of the largest gun.

Operation

After the exerciser has been placed in position, valves 38, 41, 43 and 44 are opened and a switch is closed to start the exerciser, that is, to cause pumps 17 and 18 to be driven and to cause valve member 30 to move to the position shown in Fig. 3 where it remains as long as the exerciser is in operation. Pump 17 is then caused to discharge oil first in one direction and then in the other to purge from the system any air that may be therein after which pump 17 is adjusted to

neutral and valves 41, 43 and 44 are closed. Then jack 9-11 is connected to the left end of cylinder 3 and cylinder line 42 is connected to the right end of cylinder 1 and knob 49 is rotated to open the "filling valve" as explained above. Bleeder valve 44 is then opened slightly to permit oil to escape from chamber 7 until the pressure therein and in cylinder 3 is reduced to zero after which valve 44 is closed and valve 41 is opened.

If the recoil cylinder is to be exercised independently of the recuperator cylinder, a "jack switch" is closed which causes pump 17 to deliver oil through channel 19, valve body 31, channel 37, valve 38 and jack line 39 to cylinder 10, thereby causing piston 9 to move piston 4 toward the right and piston 4 to eject oil from cylinder 3 through passage 8, chamber 7, valve 48, line 42, valve 41, channel 40, valve body 31, channel 36, meter 26, channel 63, valve body 57 and channel 64 into reservoir 21.

Meter 26 measures the oil flowing therethrough and it operates control 27 which indicates the distance piston 4 is moved and, when piston 4 has been moved to a desired position, the jack switch is released to permit pump 17 to go to zero stroke and stop further movement of piston 4. Control 27 is then adjusted until a first reversing switch is closed but that switch is ineffective unless an "automatic" switch has been closed.

A "cylinder switch" is then closed which causes pump 17 to deliver oil through channel 20 to port 58 in valve body 57 where it will move valve 55 to the position shown in Fig. 2 and then the oil will flow through valve body 57, channel 63, meter 26, channel 36, valve body 31, channel 40, valve 41, line 42, valve 48, chamber 7 and passage 8 into cylinder 3 and cause pistons 4 and 9 to move toward the left and piston 9 to eject oil from cylinder 10 through line 39, valve 38, channel 37, valve body 31 and channel 19 to the intake of pump 17.

If the displacement of cylinder 10 is less than the displacement of cylinder 3 as shown, the oil returned to pump 17 will be less than the oil discharged by it and the differential oil will be supplied to pump 17 by gear pump 18. If the recoil mechanism is for a small gun so that the displacement of cylinder 10 is greater than the displacement of cylinder 3, more oil will be returned to pump 17 than is discharged by it and the differential oil will be discharged through valve body 57, channels 65 and 22 and relief valve 25 into reservoir 21.

The oil flowing through meter 26 causes it to operate control 27 which indicates the distance piston 4 is moved and, when piston 4 reaches a position just short of the end of its stroke toward the left, the cylinder switch is released to permit pump 17 to go to zero stroke and stop further movement of piston 4. Control 27 is then adjusted until a second reversing switch is closed but that switch is ineffective unless the automatic switch has been closed.

The automatic switch is then closed to render the reversing switches effective and the second reversing switch will establish a circuit to cause pump 17 to discharge into channel 19 and thereby cause jack 9-11 to move piston 4 toward the right as explained above. When pump 17 starts to deliver oil into channel 19, it will at first draw oil from port 58 which will permit spring 66 to move valve 55 to the position shown in Fig. 1 after which pump 17 is supplied with oil by pump 18.

Piston 4 will move toward the right and meter 26 will operate control 27 until the first reversing switch closes and establishes a circuit to effect reversal of pump 17 and thereby cause piston 4 to move toward the left as explained above until the second reversing switch closes and causes piston 4 to again move toward the right. The exerciser will continue to operate automatically until piston 4 has been reciprocated a sufficient number of times to positively establish a film of oil between its periphery and the wall of cylinder 3 and then a stop switch is manually operated to stop further operation of the exerciser.

If the recoil mechanism is to be exercised as a unit, the exerciser is at first controlled manually as explained above except that the "cylinder switch" is not released when piston 4 approaches the end of its stroke toward the left but is held closed until piston 4 has stalled and enough oil has been pumped into chamber 7 to move piston 2 toward the left to a desired position.

After piston 4 stalls, pump 17 must create a high pressure in order to enable the oil to move piston 2 toward the left against the gas pressure in chamber 6, and this pressure extends from channel 40 through channel 69 to cylinder 68 and causes piston 67 to hold valve 55 in the position shown in Fig. 2.

When piston 2 reaches the desired position, the cylinder switch is released to permit pump 17 to go to zero stroke and then control 27 is so adjusted that the reversing switch is closed when piston 2 is in that position.

The automatic switch may then be closed to render the reversing switches effective and the second reversing switch will establish a circuit to cause pump 17 to discharge into channel 19 but the oil cannot at first cause jack 9-11 to move piston 4 toward the right due to the high pressure maintained in cylinder 3 and in chamber 7 by the gas pressure in chamber 6. Therefore, the oil discharged by pump 17 will flow through channel 19, valve body 57, channels 65 and 22 and relief valve 25 into reservoir 21.

At the same time, the gas pressure in chamber 6 will cause piston 2 to move toward the right and to expel oil from chamber 7 through passage 41, valve 48, line 42, valve 41, channel 40, valve body 31, channel 36, meter 26, channel 63, valve body 57 and channel 20 to the intake of pump 17 so that piston 2 can move toward the right only as fast as pump 17 draws oil from chamber 7.

When piston 2 reaches the limit of its movement toward the right, the gas pressure in chamber 6 is no longer effective to maintain pressure in the cylinder side of the circuit and, since pump 17 is drawing liquid from that side of the circuit, the pressure in port 58 will quickly drop to a value low enough to permit spring 66 to move valve 55 to the position shown in Fig. 1 thereby preventing pump 17 from continuing to discharge through relief valve 25 so that the oil from pump 17 flows to jack 9-11 and causes it to move piston 4 toward the right and the oil ejected from cylinder 3 by piston 4 to flow into reservoir 21 as explained above.

Piston 4 will move toward the right until meter 26 closes the first reversing switch to effect reversal of pump 17 as explained above. Then oil from pump 17 will move piston 4 to the limit of its movement and then will move piston 2 toward the left until meter 26 closes the second reversing switch to again effect reversal of pump 17. The exerciser will continue to operate in this manner until the pistons have been reciprocated

a sufficient number of times to assure that there is a lubricating film of oil between the periphery of each piston and the wall of its cylinder and then the exerciser may be stopped by operating a stop switch.

When pump 17 is reversed in response to piston 2 reaching the end of its movement toward the left, meter 26 is rotating at high speed and the inertia of its rotating parts causes it to overrun for an instant and thereby cause a momentary drop in pressure in channel 63 and port 58. If servomotor 67-68 were not provided, the drop in pressure in port 58 would permit spring 66 to shift valve 55 to the position shown in Fig. 1 and thereby connect channel 63 to drain channel 64 so that the high pressure in chamber 7 could operate meter 26 at a terrific speed and the pressure would drop from maximum at the inlet of meter 26 substantially to zero at the outlet thereof and thereby impose an excessive load on the meter bearings. Operation of the meter at such a high speed and under such a large pressure differential would seriously damage the meter and might ruin it. However, servo-motor 67-68 prevents valve 55 from assuming the position shown in Fig. 1 and thereby prevents damage to the meter.

If the recuperator cylinder is to be exercised independently of the recoil cylinder, valve 38 is closed, control 27 is adjusted to effect reversal of pump 17 when piston 2 reaches the limit of its movement toward the right during automatic operation of the exerciser, then pump 17 is caused to deliver oil to chamber 7 until piston 2 has been moved to a desired point, and control 27 is adjusted to effect reversal of pump 17 at that point when the exerciser is adjusted for automatic operation.

The automatic switch may then be closed which will cause pump 17 to discharge into channel 19. Since at this time the pressure in chamber 7 is causing servomotor 67-68 to hold valve 55 in the position shown in Fig. 2, pump 17 will draw oil from chamber 7 and will discharge it through relief valve 25 into reservoir 24, as explained above, so that piston 2 can move toward the right only as fast as pump 17 draws oil from chamber 7. When piston 2 reaches the limit of its movement toward the right, control 27 will effect reversal of pump 17 and piston 2 will continue to be reciprocated in this manner until the exerciser is stopped.

After the recoil cylinder has been exercised, jack 9-11 is removed and the plug replaced in the end of cylinder 3. After the recuperator cylinder has been exercised, oil is pumped into chamber 7 until piston 2 has been moved toward the left to a predetermined point. Then knob 49 is turned in a direction to permit the filling valve to close, line 42 is disconnected from charging valve 48, valve 48 is removed and the plug is replaced in the end of passage 47.

While the exerciser has been explained as being employed to exercise a particular recoil mechanism, it is capable of exercising any hydro-pneumatic recoil mechanism currently in use in this country. Also, the invention set forth herein is not limited to an exerciser nor to the specific form shown but it is susceptible of various modifications and adaptations without departing from the scope of the invention which is hereby claimed as follows.

I claim:

1. In a system including a cylinder having a piston fitted therein, means adapted when ef-

fective to maintain in said cylinder a pressure which tends to move said piston in one direction, and a hydraulic jack for moving said piston in the opposite direction, the combination of a reversible pump for delivering liquid to said cylinder or to said jack to effect movement of said piston in one direction or the other, a valve for connecting said cylinder to said pump or to exhaust, said valve normally being shiftable to a

5 first position in which it connects said cylinder to exhaust in response to said pump delivering liquid in a direction to effect operation of said jack and being shiftable to a second position in which it connects said cylinder to said pump in 10 response to said pump delivering liquid in the opposite direction, and a hydraulic actuator adapted in response to the pressure in said cylinder exceeding a predetermined value to shift said valve to said second position regardless of 15 the direction in which said pump delivers liquid.

2. In a system including a cylinder having a piston fitted therein, means adapted when effective to maintain in said cylinder a pressure which tends to move said piston in one direction, and a hydraulic jack for moving said piston in the opposite direction, the combination of a reversible pump for delivering liquid to said cylinder or to said jack to effect movement of said piston in one direction or the other, a valve connected to said cylinder and to exhaust, a first channel connecting one side of said pump to said valve, means including a second channel for connecting the other side of said pump to said jack, said valve being responsive to said pump delivering liquid into said first channel for connecting said cylinder to said first channel and normally being responsive to said pump delivering liquid into said second channel for connecting said cylinder to exhaust, and hydraulic means responsive to the pressure in said cylinder exceeding a predetermined value for adjusting said valve to cause it to connect said cylinder to said pump and thereby cause the liquid discharged from said cylinder to pass through said pump.

3. In a system including a cylinder having a piston fitted therein, means adapted when effective to maintain in said cylinder a pressure which tends to move said piston in one direction, and a hydraulic jack for moving said piston in the opposite direction, the combination of a reversible pump for delivering liquid to said cylinder or to said jack to effect movement of said piston in one direction or the other, a valve connected to said cylinder and to exhaust, said valve having a valve member which is yieldingly urged to a first position in which said cylinder is connected to exhaust and said valve being so constructed that liquid delivered thereto by said pump will shift said valve member to a second position in which said cylinder is connected to said pump, and a hydraulic actuator adapted in response to the pressure in said cylinder exceeding a predetermined value to shift said valve member to said second position regardless of the direction in which said pump delivers liquid.

4. In a system including a cylinder having a piston fitted therein, means adapted when effective to maintain in said cylinder a pressure which tends to move said piston in one direction, and a hydraulic jack for moving said piston in the opposite direction, the combination of a reversible pump for delivering liquid to said cylinder or to said jack to effect movement of said piston in one direction or the other, a control valve connected to said cylinder and to exhaust,

a first channel connecting one side of said pump to said valve, means including a second channel for connecting the other side of said pump to said jack and to said valve, a resistance valve connected to said control valve, said control valve having a valve member which is yieldingly urged to a first position in which said cylinder is connected to exhaust and said control valve being so constructed that liquid delivered thereto through said first channel will shift said member to a second position in which liquid is directed from said first channel to said cylinder to effect movement of said piston and said second channel is connected to said resistance valve so that any liquid discharged from said jack in excess of the requirements of said pump will be discharged through said resistance valve, and a hydraulic actuator adapted in response to the pressure in said cylinder exceeding a predetermined value to shift said valve member to said second position regardless of the direction in which said pump delivers liquid.

5. In a system including a cylinder having a piston fitted therein, means adapted when effective to maintain in said cylinder a pressure which tends to move said piston in one direction, and a hydraulic jack for moving said piston in the opposite direction, the combination of a reversible pump for delivering liquid to said cylinder or to said jack to effect movement of said

piston in one direction or the other, a control valve connected to said cylinder and to exhaust, a first channel connecting one side of said pump to said valve, means including a second channel for connecting the other side of said pump to said jack and to said valve, a resistance valve connected to said control valve, said control valve having a valve member which is yieldingly urged to a first position in which said cylinder is connected to exhaust and said control valve being so constructed that liquid delivered thereto through said first channel will shift said member to a second position in which liquid is directed from said first channel to said cylinder to effect movement of said piston and said second channel is connected to said resistance valve so that any liquid discharged from said jack in excess of the requirements of said pump will be discharged through said resistance valve, and a hydraulic actuator adapted in response to the pressure in said cylinder exceeding a predetermined value to shift said valve member to said second position regardless of the direction in which said pump delivers liquid, said resistance valve also being so connected to said control valve that said valve member in moving to said second position must expel liquid from said control valve through said resistance valve.

JAMES K. DOUGLAS.
